UNITED STATES PATENT OFFICE.

JOHN M. PITNEY, JR., OF LORAIN, OHIO.

CONTINUOUS TRACK-LIGHT AND AUTOMATIC SIGNAL.

No. 897,304.

Specification of Letters Patent.

Patented Sept. 1, 1908.

Application filed May 11, 1908. Serial No. 432,184.

To all whom it may concern:

Be it known that I, JOHN M. PITNEY, JR., a citizen of the United States, residing at Lorain, in the county of Lorain and State of Ohio, have invented certain new and useful Improvements in Continuous Track-Lights and Automatic Signals; and I do hereby declare the following to be a full, clear, and exact description of the invention, such as will 5 enable others skilled in the art to which it appertains to make and use the same, reference being had to the accompanying drawings, and to the letters and figures of reference marked thereon, which form a part of 10 this specification.

This invention relates to new and useful improvements in signaling devices for cars, automobiles, &c., and the object in view is to produce a light so arranged that its rays will 20 follow the track about curves and cause a signal to be sounded as the car passes about a curve.

The invention comprises various details of construction, combinations and arrangements of parts which will be hereinafter fully described and then specifically defined in the appended claims.

I illustrate my invention in the accompanying drawings, in which:—

30 Figure 1 is a side elevation showing the application of my invention to an electric car. Fig. 2 is a bottom plan view. Fig. 3 is an enlarged detail sectional view on line 3—3 of Fig. 1. Fig. 3^a is a slight modification, and Fig. 4 is a slight modification of the apparatus showing the same as applied to an automobile.

Reference now being had to the details of the drawings by letter, A designates the plat- 40 form of a car, B a bolster and C a rod vertically disposed and mounted in suitable bearings upon the car and provided with a sprocket wheel B at its lower end. E designates a chain which passes about said sprocket wheel 45 and its ends are fastened to the bolster, one upon either side of the central pivotal portion thereof, whereby, as the bolster turns, a partial rotary movement will be imparted to said rod C. Upon the upper portion of said rod 50 is fitted a lamp F having a socket F' fitting over the upper squared end of the rod, and G designates a hinged member which is adapted to fit down over the upper end of the 55 socket portion of the lamp to hold the same in place. Mounted upon said rod is a fiber block H, preferably of cylindrical form, and

has a copper band K extending partially about its circumference. A space intervenes between the ends of said copper band, forming an insulation. Metallic arms N are fastened to a block O upon the car and the free ends of said arms are adapted to contact yieldingly against the circumference of the copper band whereby, when the cylinder upon which the band is mounted is turned so 60 as to throw the free ends of said arms in contact with the copper band, the circuit will be closed and sound a signal, suitable connections being made between said arms forming contact points either with the line wire or 65 with a storage battery or other source of supply. A suitable switch lever J is mounted upon the car and has electrical connection with one pole of the battery, and J' is the contact point which is electrically connected 70 with the source of energy and against which said lever is adapted to be thrown when it is desired to put the contact points in circuit. Said switch mechanism is provided so that 75 the signal may be conveniently thrown out of operative relation if desired by the motor-man or other person when, for any purpose, it may be desired not to have the signal sounded.

In the drawings, I have shown the application of the invention to an automobile, in which the lamp S is mounted upon a spindle S' having an arm S² pivotally connected to a lever T which in turn is pivoted to a lever R having connection with a steering shaft T'. 90 Contact points I and I' are mounted upon the axle of the machine and between which said lever R is mounted and so arranged that, when the axle turns, the rays of light will be thrown in the path to be followed by the 95 wheel and sound an alarm as the circuit is closed.

In Fig. 3^a, I have shown a slight modification of the invention, in which the sprocket wheel is dispensed with and in lieu thereof a rod W is shown as connected at its one end to the bolster and its other end to the lever W' on the bottom of the lamp rod.

From the foregoing, it will be noted that, by the provision of an apparatus as shown and described, an electric or other light may be made to throw its rays upon the track to be followed by the car instead of having the light fixed as is commonly the case at present and which will throw the light directly in front of the car and not upon curves about which a car is to pass. As the bolster turns,

the light will be turned accordingly and light up the tracks about the curve and also sound a signal. When the car passes about the corner, the bolster returning to its normal position will cause the light to be thrown directly in advance of the car and the signaling will cease as the circuit is broken by the contact points of the arms leaving the copper band and coming in contact with the insulation intermediate the ends thereof.

What I claim to be new is:-

1. In combination with a car, an upright rotatable rod, a lamp mounted thereon, a fibrous cylinder fixed to said rod, a metallic band extending partially about said cylinder, contact points mounted upon the car and adapted to bear against the circumference of said cylinder, electrical circuit connections with said points, a bolster, connections between the same and said rod whereby, as the bolster turns, a rotary movement will be imparted to said rod and the circuit closed, causing a signal to be sounded simultaneously with the turning of the lamp, as set forth.

2. In combination with a car, an upright rotatable rod, a lamp mounted thereon, a fibrous cylinder fixed to said rod, a metallic band extending partially about said cylinder,

contact points mounted upon the car and adapted to bear against the circumference of said cylinder, electrical circuit connections with said points, a bolster, a sprocket wheel fixed to said rod, a sprocket chain passing about said wheel and connected to the ends of said bolster, as set forth.

3. In combination with a car, an upright rod journaled in suitable bearings therein, a sprocket wheel fixed to said rod, a bolster, a sprocket chain fastened at its ends to the latter and passing about said sprocket wheel, a lamp having a socket portion fitted over an angular portion of said rod, a hinged lamp retaining member mounted upon the car and engaging said socket member, a cylinder of fibrous material upon said rod, a metallic band partially surrounding said cylinder, contact points mounted upon the car and adapted to bear against said band and cylinder, and electric connections with said points, as set forth.

In testimony whereof I hereunto affix my signature in the presence of two witnesses.

JOHN M. PITNEY, JR.
